[57] CLAIM

The ornamental design for an end standard for a seat, as shown and described.

DESCRIPTION

FIG. 1 is a left side elevational view of an end standard for a seat, showing my new design;

FIG. 2 is a right side elevational view thereof;

FIG. 3 is a top plan thereof;

FIG. 4 is a bottom plan view thereof; and

FIG. 5 is an end elevation view, the opposite end being a mirror image thereof.

FIG. 1.

FIG. 2.

FIG. 3.

FIG. 4.

FIG. 5.
